Primary Examiner — Kevin K Rudzinski*(74) Attorney, Agent, or Firm* — Morgan, Lewis & Bockius LLP(57) CLAIM

The ornamental design for a garment, as shown and described.

DESCRIPTION

FIG. 1 is a front perspective view of a garment in a first use condition showing my new design;

FIG. 2 is a front elevational view thereof;

FIG. 3 is a right-side elevational view thereof;

FIG. 4 is a rear elevational view thereof;

FIG. 5 is a left-side elevational view thereof;

FIG. 6 is a top plan view thereof;

FIG. 7 is a bottom plan view thereof;

FIG. 8 is a front perspective view of the garment of FIG. 1 in a second use condition;

FIG. 9 is a front elevational view thereof;

FIG. 10 is a right-side elevational view thereof;

FIG. 11 is a rear elevational view thereof;

FIG. 12 is a left-side elevational view thereof;

FIG. 13 is a top plan view thereof; and,

FIG. 14 is a bottom plan view thereof.

The short broken lines depict stitching which forms part of the claimed design. The long, evenly spaced broken lines depict environmental features that form no part of the claimed design.

1 Claim, 14 Drawing Sheets(56)
